UNITED STATES PATENT OFFICE.

JOHN R. HARPER, OF MENARD, ILLINOIS.

MOLD.

1,120,478.

Specification of Letters Patent.

Patented Dec. 8, 1914.

Application filed December 8, 1909. Serial No. 532,003.

To all whom it may concern:

Be it known that I, JOHN R. HARPER, a citizen of the United States, residing at Menard, in the county of Randolph and State of Illinois, have invented new and useful Improvements in Molds, of which the following is a specification.

This invention relates to improvements in molds and has particular application to a sectional mold.

In carrying out the present invention, it is my purpose to provide a sectional mold which will embody among other features a base member having a vertically disposed core and end and side walls mounted upon the base member and surrounding the core, one of such walls carrying a hollow semi-circular core extending inwardly thereof at right angles to the first core and having the inner end thereof recessed to lug the adjacent portion of said first core so that in the molding of the block right angular passages may be formed therein.

It is also my purpose to provide a mold of the class described which will embrace the desired features of simplicity, efficiency and durability, one which may be readily assembled and knocked down and one which may be manufactured and marketed at a minimum expense.

With the above and other objects in view, the invention consists in the construction, combination and arrangement of parts hereinafter set forth in and falling within the scope of the claim.

In the drawings, forming a portion of this specification and in which like numerals of reference indicate similar parts in the several views:—Figure 1 is a perspective view of a series of blocks constructed by my improved mold, the said blocks being arranged with respect to each other to form a chimney. Fig. 2 is a perspective view of the mold. Fig. 3 is a plan view of the base member or element forming the platform for the mold. Fig. 4 is a transverse section taken through the mold. Fig. 5 is a detail perspective view of one of the side members of the mold. Fig. 6 is a perspective view of one of the end members of the mold. Fig. 7 is a perspective view of a different form of base member or element forming the platform in the construction of another form of block from that shown in Fig. 2. Fig. 8 is a perspective view of another form of side member. Fig. 9 is a perspective view of a

still further form of side member. Fig. 10 is a similar view of another form of side member. Fig. 11 is a perspective view of another form of base member or element 60 forming the platform in the construction of another form of block. Fig. 12 is a perspective view of the partition plates.

Referring now more particularly to the drawings, and with particular reference to Figs. 2, 3 and 4 thereof, there is shown a mold 1 comprising a base member or element 2 adapted to form the platform for the mold. The base member or element 2 is provided with a rabbeted edge portions 3, and 70 as shown, the said member or element is formed at one side with an offset portion 4 for a purpose to be hereinafter more fully described. A vertically extending core 5 is carried by the base member or element and 75 is preferably formed integral with the same as will be clearly seen upon reference to Fig. 4 of the drawings, but I do not desire to limit myself to the formation of the core with respect to the base member or element 80 as it is only obvious that the core could be formed separately with respect to the member or element and detachably secured thereto in any suitable manner should it be so desired. The core 5 is disposed upon the 85 base member 2 in such position with respect to the front and rear edges of the member or element so that the front and rear walls of the core are equally spaced from the front and rear edges of the base member or element 90 2.

The mold is provided with a front wall 6 having an offset portion 7 to conform to the offset portion 4 of the base member or element and the lower edges of this wall are 95 seated in the rabbeted portion 3 at the front edge of the base member or element. The laterally extending wing portions 8 and 8' of the front wall extend outwardly so that their outer edges are disposed in line with 100 the ends of the end portions of the base member or element. The wing portion 8 of the front wall is provided at the ends thereof with straps 9 adapted to aline with similar straps 10 at one end of an end wall 105 11. The straps 9 and 10 are provided with alining passages to receive removable keys or suitable fastening devices 12 so that the front wall can be easily detached from the end wall 11 as will be appreciated. The 110 rear wall 13 of the mold is constructed from a flat piece of metal or suitable material and

is connected to an end wall 14 by straps 15 similar to the straps 9 and 10. The opposite end of the rear wall 13 is connected to the rear end of the end wall 11 in a manner similar to the strap connections hereinbefore described. The wing portion 8' of the front wall 6 carries a staple or the like 16 which has pivotally connected thereto a strap or hasp element 17 having a right 10 angularly extending portion 18 provided with a longitudinally extending slot 19 adapted to receive a rotatable locking key or fastener 20 engaged with the end wall 14. The top of the core 5 lies flush with the 15 upper edges of the walls of the mold so that when a block is formed its upper surface will be a plane surface.

The knuckles of the straps on one wall section are arranged in coincidence with the 20 knuckles of the straps on the adjacent wall section when the sections are set up, and as shown, the said knuckles embrace the wall sections so as to hold them rigid. This is not only desirable for the reason that the 25 blocks can be molded with accuracy but that considerable strain is relieved from the pivot pins 12. The pins 12 are removable for the purpose of allowing them to be interchangeably connected with any of the mold section 30 walls.

From the construction of mold described in Figs. 2, 3 and 4 of the drawings, it will appear that a block as illustrated at A in Fig. 1 of the drawings is formed having outwardly extending wings A' and a centrally located outwardly extending or offset portion B. The provision of the core 5 is such that the block A is formed with a vertically extending passage or flue as will be readily understood.

Upon reference to Fig. 7 of the drawings, the base member or element 21 is somewhat similar to the element or member 2 previously referred to, but in this instance the element or member carries at one end an offset portion 22 having a semi-cylindrical vertically extending core 23. The wall 24 carries a strap or hasp 26 similar to the strap or hasp 17. When the wall 24 is connected with the walls 11, 13 and 14 and applied to the base member or element 21 it will be seen that when concrete or other plastic substance is poured into the mold a block will be formed like the one shown at C in Fig. 1 of the drawings, the said block being provided with an offset portion C' and by the provision of the semi-cylindrical core 23 the block C will consequently be provided with a correspondingly shaped passage or flue.

Upon reference to Fig. 9 of the drawings, it will be seen that I employ a front wall 27 having an offset portion 28 which carries at its lower extremity an arcuate inwardly extending core 29. I use in connection with the wall 27 the end walls and the

rear wall hereinbefore described and use the plurality of walls in combination with the base member or element 21, and by so doing it is obvious that the upper outer edge of the core 29 will lie against the end wall 11 and the inner edge of the core will lie against a portion of the core 23 so that when plastic substance is poured into the mold a block like the one shown at D in Fig. 1 of the drawings will be formed and provided with an offset portion D' having an arcuate horizontally disposed flue forming cavity D². By providing the core 23, the said block D will also have formed therein, as will be understood, a vertical flue or passage adapted to align with the flue or passage formed in the blocks B and C. The block E used in conjunction with the block B is formed in a manner similar to the block D, but in lieu of the wall 27 I provide a wall 30 having an offset portion 31 that carries a core 32. The difference in this form of wall is that the core 32 is formed or located at the right hand end, whereas in the wall 27 the core 29 is located in the left hand end. The block E, will, however, be provided with an offset portion E' disposed in line with the offset portion D' of the block D and will carry a passage E² disposed in line with the cavity D².

Upon reference to Fig. 8 of the drawings, there will be seen a front wall 33 having a centrally located offset portion 34 and outwardly extending wing portions 35. This form of wall is used in conjunction with the base member or element 2 and with the walls 11, 13 and 14 described in the form of my invention shown in Figs. 2, 3 and 4. The offset portion 34 is provided with an inwardly directed semi-cylindrical horizontally disposed core 36, the lower side edges of which are adapted to rest upon the platform when the mold sections or walls are in an operative position. The core 36 is provided at the rear edge thereof with a concavity 37 arranged to tightly hug a portion of the core 5. When constructing a block, using the walls 11, 13, 14 and 33 it will be seen that after concrete substance has sufficiently hardened to form a substantial block, the block may be inverted and will be of a form shown at F in Fig. 1 of the drawings and will carry an offset portion F' and outwardly extending wings F² similar to the wings A' of the block A. By providing the core 5 the block F will have a centrally located vertically extending passage or flue, and the offset portion F' of the block will be formed with a semi-cylindrical cavity or passage F³ located directly beneath the cavity D², and the said cavity F³ will consequently form together with the cavity D² a cylindrical flue for receiving the end of a pipe section.

The wall 30 hereinbefore described, in

view of the fact that it carries an offset portion 31 located at the right hand end instead of at the left hand end shown in the wall 27 in Fig. 9 of the drawings is used in conjunction with a base member or platform 38 similar to the base member or element 21, the difference being in the provision of an offset portion 39 at the right hand end and a vertically extending semi-cylindrical flue 40 projecting upwardly from the offset portion 39.

The construction of mold is such that the blocks when formed will all be of a uniform length, and should I desire to form blocks of less length than I have hereinbefore shown, removable partition strips 41 are used and are adapted to be disposed between the front and rear walls of the mold and may be clamped thereto temporarily in any desirable manner. The partition strips 41 are provided with handles 42 at their upper ends.

A mold as herein constructed by me will be found extremely useful in view of the fact that blocks of various character may be formed and assembled to provide a chimney

as shown in Fig. 1 of the drawings. The construction of blocks is such that a plurality of spaces G are provided between the blocks to receive joists or beams in building 30

I claim:—

A mold comprising a base member having a vertically disposed core, end walls, a rear wall, a front wall coöperating with said end and rear walls, said walls being positioned upon the marginal edges of the base member and inclosing the core and spaced apart therefrom, detachable connections between said walls, and a hollow semi-circular core 40 carried by said front wall and extending inwardly thereof at right angles to the first-mentioned core and having the inner end thereof recessed to hug the adjacent portion of the first-mentioned core. 45

In testimony whereof I affix my signature in presence of two witnesses.

J. R. HARPER.
